UNITED STATES PATENT OFFICE.

JACOB W. WENGER, OF BOTTINEAU, NORTH DAKOTA.

NOSE-BAG SUPPORT.

1,084,985.

Specification of Letters Patent. Patented Jan. 20, 1914.

Application filed June 13, 1913. Serial No. 773,482.

To all whom it may concern:

Be it known that I, JACOB W. WENGER, a citizen of the United States, residing at Bottineau, in the county of Bottineau and 5 State of North Dakota, have invented new and useful Improvements in Nose-Bag Supports, of which the following is a specification.

This invention relates to nose bag supports.

The principal object of the invention is to provide simple and efficient means for supporting the nose bag in proper spaced relation on the horse's body so that the horse 15 may conveniently obtain the feed from the bag at all times.

Another object of the invention is the provision of a novel bag supporting device which may be folded into compact space 20 when not in use and which is supported from the hames so as to take the weight off of the horse's head.

Still another object of the invention is the provision of a device of this character which 25 is adjustable so as to provide for the accommodation of bags of different sizes.

Further objects of the invention will appear as the following description is read in connection with the accompanying drawings, which form a part of this application 30 and in which:—

Figure 1 is a side elevation of the device shown applied, the horse's head being indicated in dotted lines. Fig. 2 is a front 35 elevation. Fig. 3 is a top plan view with a portion of the side straps removed. Fig. 4 is a perspective view of the folded frame with the straps and supporting chain broken away.

Referring more particularly to the drawings, 40 1 represents a bag supporting bar which is provided at its forward end with a closed slot 2 adapted to receive the looped end of the front bag holding strap 3. Pivoted to the center of the bar 1 is a cross bar 4 which may be alined with the bar 1, as shown in Fig. 4, or it may extend at right 45 angles thereto, as shown in Fig. 3, in bag supporting position. The opposite ends of 50 the bar 4 are provided with closed slots 5 adapted to receive the side bag holding straps 6. These straps extend vertically of the bag 7 and are provided at their upper ends with snaps 8 to engage in the rings 9

connected to the upper end of the bag, the 55 snaps being secured in adjusting loops 10.

Intermediate the adjusting loops 10 and the connection of the straps 6 with the bar 5 they have connected thereto the bag and the front straps 11 and 12, respectively. The 60 front strap is provided with an adjusting loop 13 which engages a ring 14 in the extended end of the bag strap 11, while the bag strap 11 is provided with an adjusting loop 15 having a snap 16 adapted to engage a 65 ring 17 in the extended end of the front strap 12, the bag thereby being disconnectible, for a purpose to be hereinafter described.

Extending vertically from the rear end 70 of the bar 1 is a lug 18 having pivoted thereto one link of an adjustable brace bar 19. This bar consists of a plurality of links pivoted together, each being provided with a notch 20 adapted to engage limiting pins 75 21 and 22, the former being arranged on the bar 1 and the latter being arranged on the links adjoining the pivotal connection. The rear link, as shown, is provided with a snap 23 which is adapted to engage a suitable part on the lower end of the hames 24; this being a pivotal connection permits the 80 free lateral and vertical swinging of the brace bar 19.

Projecting laterally from the link which 85 is pivoted to the bar 1 is an eye rivet 25 to which is connected a chain 26 having a grab hook 27 at its opposite end. This chain is adapted to be thrown around the upper end of the hames so as to adjustably 90 support the brace bar and the bag supporting structure which is pivoted thereon. Intermediate the length of the chain a second chain 28 is secured, the opposite terminal end of which is provided with a hook 29 95 for engagement with a rivet 30 on the rear. This connection is made removable so that when the device is folded as shown in Fig. 4 the chain 28 may be disconnected and the chain 26 wrapped around the parts so as 100 to hold them in folded position.

Connected to the rivet 25 is a short chain 31 provided with a ring 32 in its end through which the bag strap 11 is passed. This connection is made so as to prevent the bag 105 from moving forwardly over the supporting bags 1 and 4. It will be noticed that the bag proper is suitably supported upon the head

of the animal but the weight of the feed is supported by the structure just described. In other words, the bag is simply prevented from collapsing by being connected in the usual manner with the head strap.

In the claims I shall make use of the terms "bag supporting structure" and "frame" and where the first term is used I wish it to be understood as defining the cross bars 1 and 4 and the straps connected thereto and the latter term will be used to define the cross bars.

What is claimed is:—

1. A device of the class described comprising a bag supporting frame consisting of pivoted cross bars, means connected to the frame for holding the bag in position thereon, a brace connected to one of the cross bars of the frame, means for connecting the brace bar to the lower part of the hames and means connecting the bag hold-

ing means and the brace for preventing the bag from shifting on the frame.

2. In combination, a foldable bag supporting frame, a folding brace bar pivotally connected thereto, means for pivotally connecting the brace bar to the lower part of the hames, an adjustable, flexible element for connecting the brace bar to the upper part of the hames and an adjustable bag 30 supporting structure for securing a bag to the frame, together with means to prevent the bag from shifting on the frame which is removably connected with the supporting structure.

In testimony whereof I affix my signature in presence of two witnesses.

JACOB W. WENGER.
